(57) **CLAIM**

I claim the ornamental design for an agricultural tilting bearing support, as shown and described.

DESCRIPTION

FIG. 1 is a perspective view of a agricultural tilting bearing support showing my new design;

FIG. 2 is a side elevation view thereof, the opposing side elevation view being a mirror image;

FIG. 3 is a top plan view thereof;

FIG. 4 is a bottom plan view thereof; and,

FIG. 5 is a front elevation view thereof, the rear elevation view being a mirror image.
